PAPER TOWEL HOLDER

Earl B. Hockenberry and Gerald W. Lewis, Emporium, Pa., assignors to Lew-Hoc Wood Products Company, Inc., Emporium, Pa., a corporation of Pennsylvania

Filed Aug. 20, 1969, Ser. No. 18,770

Term of patent 14 years

Int. Cl. D6—01

U.S. Cl. D52—2

FIG. 1

FIG. 2

FIG. 3

FIG. 4

FIG. 1 is a top plan view of the paper towel holder;
FIG. 2 is a front view of the paper towel holder;
FIG. 3 is a side view of the paper tower holder;
FIG. 4 is a rear view of the paper towel holder.

I claim:

The ornamental design for a paper towel holder, substantially as shown.
